UNITED STATES PATENT OFFICE.

WILLIAM P. THOMSON AND SAMUEL G. THOMSON, OF PHILADELPHIA, PENNSYLVANIA,
ASSIGNORS TO THOMSON-THOMSON COMPANY, OF PHILADELPHIA, PENNSYLVANIA,
A PARTNERSHIP.

RAIL-JOINT.

972,735.

Specification of Letters Patent. Patented Oct. 11, 1910.

Application filed December 27, 1907. Serial No. 408,296.

To all whom it may concern.

Be it known that we, WILLIAM P. THOMSON and SAMUEL G. THOMSON, both of Philadelphia, in the county of Philadelphia and State of Pennsylvania, have invented a new and useful Improvement in Rail-Joints, of which the following is a full, clear, and exact description, reference being had to the accompanying drawings, forming part of this specification, in which—

Figures 1 to 3 are sectional views showing different forms of our improved rail joint.

Our invention has relation to the class of rail joints, and is designed to provide an insulated rail joint which combines the features of cheapness, safe insulation and hard service, and what is most important, great stiffness without being too rigid, all of which are fundamental requirements.

The main feature of our invention consists in a rail joint having a splice bar which has a continuous upright girder and a flexible portion located adjacent to the vertical plane of the outer edge of the rail base. The continuous girder extends from the top to the bottom of the bar and lies in a generally upright position; we desire, in some cases to bend the lower portion of the upright girder slightly inwardly for purposes explained hereafter. Our bar contacts only with the broad insulated faces of the base portion of the rail, and is kept at a considerable distance from the head of the rail where the insulation is invariably pinched out and destroyed sufficiently to make a metallic contact between the rail and the bar in the insulated rail joints heretofore used.

The precise nature of our invention will be best understood by reference to the accompanying drawings, wherein we have shown several modified forms thereof, it being premised however that the invention is susceptible of various other modifications without departing from the spirit and scope of our invention.

In the drawings, the numeral 2 wherever seen designates the rail, 3 the splice bars, and 4 and 5 the joint bolts, the former being the bolts which extend through the web portion of the rail, and the latter the bolts which extend below the rail base.

In the form of the invention shown in Fig. 1, the lower part of the bar 3 is formed

with a jaw portion 6 which extends around the base flange of the rail, a piece 7 of insulation being interposed between it and the upper surface and outer edge of the base of the rail, and a block 8 of wood or other similar material being placed underneath the base of the rail and supported by the lower jaw. The upper portion of the bar is, as shown, separated to a considerable distance from the rail with an interposed block 8 of wood or similar material through which the bolts 4 extend. The lower portion of the bar 3 also has a depending bolting flange 9 for the bolts 5.

Fig. 2 shows a form similar to Fig. 1, but the upper and lower bolting flanges of the bar 3 form a straight vertical girder.

The modification shown in Fig. 3 is similar to the form shown in Fig. 1, except that a wooden block 8a is interposed between the outer side of the upright member 3 and the nut 4, in lieu of the insulation.

In the case where the wooden blocks are used above or below the rail base metal facing plates or separate insulating material may be placed between the block and the rail or between the block and the splice bar, without departing from the spirit of our invention.

It will be noted that in all the forms shown and described, the only contact between the bar and the rail is at the base of the rail, the upper member of the bar being kept at a considerable distance from the web and head of the rail. It has been found in practice that the insulation of a rail joint is almost invariably pinched out and destroyed at the head of the rail so as to permit metallic contact between the rail and the bar. By keeping the metal parts away from the head of the rail, there is no possibility of getting a metallic contact between the rails and the bar, except through the broad bearing faces on the base of the rails. This construction also greatly lessens the amount of insulating material required, and with the various arrangements of the wooden blocks makes a very cheap insulated joint. It will be noted that the block as shown in the upper pocket between the bar and the web of the rail is not essential to the splicing or stiffening capacity of the joint, but that it can be omitted; or this pocket can be filled with any kind of insulating material which will exclude any substance which might otherwise get into it.

and make contact between the two rails. The principal purpose of the block is as a filler, and a protection against the weather for the inside insulating parts.

5 It is essential that when blocks are used in the pockets above the rail base, they shall not be of greater resistant capacity to compression than the insulating material contacting with the rail base. Otherwise, the 10 clamping efficiency of the bars on the broad bearing faces of the rail base would be neutralized. Our preferred form has vertical upper and lower bolting members, near the outer edge of the rail base, with inwardly 15 extending resilient bearing ribs in order to give great stiffness to the bar and at the same time form an elastic and springy structure which is very much less liable to damage the insulation than a rigid longitudinal 20 member having a solid bearing under it. Such arrangement of the lower member together with the inwardly extending bearing member above the rail base and the upwardly extending bolting member inclosing the block 25 gives a very cheap construction and at the same time an insulated joint which is stiffer and safer against damage than any yet constructed. It is essential to have the bolts above and below the rail base in order to get adequate 30 clamping effect. It is also very essential for the bar to have a narrow neck or flexible section extending around the rail base and connecting the upper and lower portions of the bar, in order that the action of the upper 35 and lower bolts will effectively clamp the rail base. We claim as entirely new the combination of the two bolting leverage members acting on flexible inwardly extending clamping flanges in such a way as to 40 give a clamping action on the top and bottom of the rail base in addition to the direct horizontal pull of the bolts. This clamping action is greatest adjacent to the rail web where it is most effective in holding the rails 45 to line and surface and yet the flexibility of the inwardly extending jaws at this point prevents the insulation from being pinched out as is the case with bars bolted above and below the rail base and having their bolting 50 members joined to the base clamping members adjacent to the rail web. The narrow neck portion around the outer edge of the rail base gives a great closing-in or horizontal clamping elasticity to the bars and yet 55 does not perceptibly decrease the great vertical stiffness obtained by the almost continuous vertical girder formed by the bolting members. The flexible inwardly extending clamping jaws also afford a maximum 60 lateral stiffness to the bar with a minimum amount of metal which with the clamping action gives an insulated joint which will be very effective in maintaining the rails in line and surface by its action on the base of the 65 rail only and without any assistance from a

bearing under the head of the rail where insulation has hitherto been almost immediately pinched out between very rigid faces.

Our new construction combines the greatest stiffness coupled with the greatest elasticity in relieving the insulating bearing faces and gives a bar made with a minimum amount of metal that will always adjust itself to a perfect fit and stay in a tightened position for a long time. The bolts above and below the rail base increase the bolting capacity to a maximum. They maintain a perfectly flat fit between all the bearing faces and do not allow the bars to kick out below and thus throw all the pressure on one part of the insulation which soon results in its destruction.

While we have shown our invention as applied to ordinary T-rails as an insulated joint, it will be obvious that it is applicable to rails of other sections, and that certain insulating parts can be omitted or replaced by metal parts to afford a positive joint for regular service, or to afford an insulated joint which contacts with one rail and is insulated from the other rail end.

Although we show wooden blocks in our drawings, we may use in their place any kind of filling material that will act as an insulator and it is with this interpretation that we use the word "block" in our claims.

We claim:—

1. In a rail joint, a splice bar having two upright bolting members located adjacent to the outer edge of the rail base, flanges projecting inwardly to form a recess to receive the greater portion of one of the base flanges of the rail, and bolting means above and below the rail base to clamp said inwardly projecting flanges to the rail base.
2. In a rail joint, a splice bar having an upright bolting member above the rail base and another upright bolting member below the rail base, both of which are located adjacent to the outer edge of the rail base, a flange projecting inwardly along the rail base from each of said bolting members to clamp the rail base, and bolting means for holding said splice bar to the rail.
3. In a rail joint, a splice bar having two upright bolting members lying in planes adjacent to the outer edge of the rail base, bolting means applied to said bolting members above and below the rail base, and base-clamping flanges projecting inwardly to form a recess which is contractible by the application of said bolting means.
4. In a rail joint, a splice bar having an upright bolting member joined to an inwardly projecting member above the rail base and another upright bolting member joined to an inwardly projecting member below the rail base, each of which junctures forms an L-shaped structure having its apex adjacent to the outer edge of the rail base,

and bolting means above and below the rail base to clamp said splice bar to the rails.

5. In a rail joint, a splice bar having an L-shaped portion above the rail base and embracing a filling block between its members and the rail, another L-shaped portion below the rail base, and bolting means above and below the rail base to clamp said parts to the rails.

10 6. In a rail joint, a splice bar having an upright bolting member above the rail base, a filling block between said member and the web of the rail and another block on the outside of said member, another upright bolting member below the rail base, both of which bolting members are located adjacent to the outer edge of the rail base, a flange projecting inwardly from each of said bolting members to form a recess to receive the
15 greater portion of one of the base flanges of the rail, and bolting means above and below the rail base to clamp said parts and the rails together.

7. In a rail joint, a splice bar having two
20 upright bolting members located adjacent to

the outer edge of the rail base, flanges projecting inwardly to form a recess to receive the greater portion of one of the base flanges of the rail, bolting means above and below the rail base to clamp said inwardly projecting flanges to the rail base, and means for insulating said splice bar from the rail.
30

8. In a rail joint, a splice bar having two upright bolting members located adjacent to the outer edge of the rail base, flanges projecting inwardly to form a recess to receive the greater portion of one of the base flanges of the rail, and bolting means above and below the rail base to clamp said inwardly projecting flanges to the rail base, the upper 35 upright bolting members being entirely outside of the heads of the rails.
40

In testimony whereof, we have hereunto set our hands.

WILLIAM P. THOMSON.
SAMUEL G. THOMSON.
